(57) **CLAIM**

I claim the ornamental design for a shoe horn, as shown and described.

DESCRIPTION

FIG. 1 is a front perspective view of the shoe horn in accordance with my new design;

FIG. 2 is a rear perspective view thereof;

FIG. 3 is a front view thereof;

FIG. 4 is a rear view thereof;

FIG. 5 is a left hand side view thereof;

FIG. 6 is a right hand side view thereof;

FIG. 7 is a top view thereof;

FIG. 8 is a bottom view thereof; and,

FIG. 9 is a side elevational view thereof, the broken line showing of the shoe is for illustrative purposes only and forms no part of the claimed design.
